UNITED STATES PATENT OFFICE.

WALTER B. UFFERT, OF JAMAICA, NEW YORK.

BRAKE ATTACHMENT.

1,399,591.

Specification of Letters Patent. Patented Dec. 6, 1921.

Application filed November 12, 1919. Serial No. 337,576.

To all whom it may concern:

Be it known that I, WALTER B. UFFERT, a citizen of the United States, residing at Jamaica, Long Island, in the county of Queens and State of New York, have invented certain new and useful Improvements in Brake Attachments; and I do hereby declare the following to be a full, clear, and exact description of the invention, such as will enable others skilled in the art to which it appertains to make and use the same.

This invention relates to new and useful improvements in brake attachments and has for one of its objects the provision of means 15 for positively locking either pneumatic or manually operated brakes of a car in an applied position so as to obviate any danger of the brakes being accidentally released while the car is unattended.

Another object of this invention is the provision of a brake attachment of the above 20 stated character, which shall be simple, durable and efficient, and which may be manufactured and sold at a comparatively low 25 cost.

With these and other objects in view as will become more apparent as the description proceeds, the invention consists in certain novel features of construction, combination, and arrangement of parts as will be hereinafter more fully described and claimed.

For a complete understanding of my invention, reference is to be had to the following 35 description and accompanying drawings, in which,

Figure 1 is a side elevation of a brake attachment constructed in accordance with my invention and illustrating the same applied to a car,

Fig. 2 is a detail view partly in section of the same,

Fig. 3 is a transverse sectional view taken on the line 3—3 of Fig. 2,

Fig. 4 is an end view of the device illustrating the manner of operating the dog.

Fig. 5 is a detail sectional view, illustrating a two-way valve.

Referring in detail to the drawings, the 50 numeral 1 indicates a car having thereon an air-brake system 2 consisting of a reservoir 3 to which are connected pipes 4 leading to controlling valves 5. The controlling valves 5 are located in each end of the car 55 and have connected thereto pipes 6 that lead

to a brake cylinder 7. The valves 5 also have connected thereto exhaust pipes 8.

The brake cylinder 7 is supported by hangers 9 secured to the bottom of the car 1 and has reciprocally mounted therein a 60 piston 10 to which is connected a piston rod 11. The piston rod 11 by means of a pivot pin 11' is adapted to be connected to the ordinary brake mechanism of the car (not shown). A spring 12 is located within the 65 cylinder 7 for the purpose of forcing the piston 10 to its non-brake applying position when the air has been exhausted from the cylinder.

The foregoing description relates to a well 70 known construction of air-brake system to which my invention is applied.

Upper and lower pairs of brace rods 13 have one of their ends secured to the brake cylinder 7 and their other ends connected to 75 hangers 14. The upper ends of the hangers 14 are secured to the under face of the car 1. A roller 15 is journaled between the hangers 14 and has slidably mounted thereon a rack bar 16 which is pivoted to 80 the piston rod 11. A shaft 17 is carried by the hangers 14 and has journaled thereon a dog 18 adapted to engage the teeth of the rack bar 16 for preventing the piston 10 from returning under the influence of the 85 spring 12 to a non-brake-applying position. The dog 18 is normally held out of engagement with the rack bar 16 by means of a spring 18' secured to the same and to the car.

A lever 19 is secured to the shaft 17 and has 90 pivoted thereto a piston rod 20 slidable within an auxiliary cylinder 21 and carries upon its inner end a piston 22. The cylinder 21 is provided with an intake end to which is connected an intake pipe 23. The pipe 23' 95 connects with a pipe 24 which is in turn connected to the exhaust pipes 8 by means of two-way valves 25 of any desired construction.

A coil spring 26 is located within the auxiliary cylinder 21 for the purpose of normally urging the piston 22 in the direction of the intake end for the purpose of aiding in retracting the dog 18 from engagement with the rack bar 16.

In operation after the brakes have been applied in the usual manner by the controlling valves 5, the air is exhausted from the cylinder 7 through pipe 6 and controlling valve 5 and at the same time the two-way 110

valves 25 are positioned to direct the exhaust air to the auxiliary cylinder 21 by way of the pipes 24 and 23 which forces the piston 22 against the tension of the spring, throwing the dog 18 downward in engagement with the teeth of the rack bar 16, positively locking the brakes in an applied position. When the brakes are applied in the usual manner, the rack bar 16 is moved forwardly during the forward movement of the piston 10. When it is desired to release the brakes after being positively locked by the device, the two-way valves 25 are so positioned that the air within the auxiliary cylinder 21 may exhaust outwardly through the ports 25' of said valves 25.

If desired, the device can be manually operated, instead of being operated by pneumatic means and in this case, an arm 28 is secured to the shaft 17 and has connected thereto rods 29 which are in turn connected to levers 30. The levers 30 are pivoted adjacent the ends of the car in convenient reach of the motorman or operator and have connected thereto foot pedals 31 so that upon pressing the foot pedals, the dog 18 will be thrown into engagement with the rack bar.

While I have shown and described the preferred embodiment of my invention, it will be understood that minor changes in construction, combination, and arrangement of parts may be made without departing from the spirit and scope of the invention as claimed.

Having thus described my invention, what I claim is:—

1. In combination, an air brake system including a cylinder having a piston connected to a brake rigging, and an air pressure source connected to the cylinder and

equipped with a controlling valve having an exhaust pipe, a rack bar secured to the piston and movable therewith, an auxiliary cylinder, a piston in said last cylinder, a pivoted dog connected to the last piston and adapted to be moved by the latter to engage the rack bar, a pipe connected to the auxiliary cylinder, and an auxiliary controlling valve connecting said last pipe to the exhaust pipe for directing air pressure exhausted from said first controlling valve into the auxiliary cylinder for actuating the dog and said auxiliary controlling valve being adapted to be positioned to permit the exhaust air pressure from the first named valve to escape to the atmosphere and to permit the air pressure to escape from the auxiliary cylinder.

2. An air brake attachment comprising a rack bar secured to the piston of an air brake system, a pivoted dog associated with the rack bar and normally disengaged therefrom, a piston connected to said dog, a cylinder for said last piston, a pipe connected to the cylinder, a two-way valve connecting said pipe to the exhaust pipe of the controlling valve of the air brake system for directing air pressure from said controlling valve into the cylinder for actuating the dog to hold the rack bar, and said two-way valve capable of being positioned to permit the air pressure from the controlling valve to escape to the atmosphere and also permit the air pressure from the cylinder to escape.

In testimony whereof I affix my signature in presence of two witnesses.

WALTER B. UFFERT.
